UNITED STATES PATENT OFFICE.

JOHN ARTHUR BJUR, OF KULM, NORTH DAKOTA.

REVERSING MECHANISM.

SPECIFICATION forming part of Letters Patent No. 743,228, dated November 3, 1903.

Application filed March 11, 1903. Serial No. 147,324. (No model.)

To all whom it may concern:

Be it known that I, JOHN ARTHUR BJUR, a citizen of the United States, residing at Kulm, in the county of Lamoure and State of North Dakota, have invented a new and useful Reversing Mechanism, of which the following is a specification.

This invention relates to mechanism for reversing engines and varying the position of their valves; and it consists in the features hereinafter described and claimed.

In the accompanying drawings, Figure 1 is a top plan view of one embodiment of the invention. Fig. 2 is a central vertical section of Fig. 1, showing the eccentric and eccentric-support at its intermediate position. Fig. 3 is a vertical section showing the position of the eccentric and eccentric-support at one extreme point of its movement. Fig. 4 is a vertical section showing the position of the eccentric and eccentric-support at the other extreme position. Fig. 5 is a top plan view of a modified form of my invention, and Fig. 6 is a sectional view on the line 6-6 of Fig. 5 looking in the direction of the arrow.

Like characters indicate corresponding parts throughout all the figures of the drawings.

The numeral 10 designates a crank-shaft of an engine which is provided with one or more spiral ribs 11 encircling the shaft. About said shaft is a sleeve 12, having an opening 13, through which the shaft extends eccentric to its axis and provided along the walls of said opening with spiral grooves 13^a, into which the ribs 11 project. The sleeve may carry a collar 14, turning loosely thereon in a groove 15, and to this collar is connected the usual form of a reversing-lever. Collars 16 may be fastened to the shaft at each side of the sleeve to limit its movement therealong. About the sleeve is a valve-operating member of the engine, here shown as an eccentric 17, having encircling it the strap 18 with the connecting-rod 19. The eccentric-opening 20 of this main eccentric is preferably provided with one or more spiral ribs or projections 21, which coöperate with spiral grooves 22 in the exterior of the sleeve 12. Stop members 24 are secured to any fixed portion of the engine-frame, contact with the opposite sides of the eccentric to prevent its

lateral movement while permitting its free rotation. The elements are so proportioned and limited in movement and their grooves and engaging projections so formed that when the reversing-lever is at one extreme position the sleeve will be in proximity to one of the stop-collars 16, and the axes of the eccentrics will lie upon the same side on the axis of the crank-shaft, giving sufficient throw to move the valve through its full stroke. Then as the sleeve is moved toward the opposite stop-collar by the reversing-lever the eccentric axes are moved about the shaft by the engagement of the spiral ribs and projections in opposite directions, gradually decreasing the stroke of the valve until at the middle position of the reversing-lever they are at substantially equal distances upon opposite sides and the valve will receive no motion. As the reversing-lever is pushed by the central position the eccentric axes begin to approach one another from opposite directions and the valve reverses the engine. Finally, as the movement is continued to the limit and the sleeve reaches the opposite stop-collar the valve has imparted to it the full reverse stroke.

It will be seen that this improved reversing mechanism is extremely compact and simple to make and use, that it has few contacting surfaces to wear loose, and that it will operate smoothly and effectually.

In the modification shown in Figs. 5 and 6 the operation is the same. In this form the sleeve 25 is provided with straight grooves on both its exterior and interior, the exterior grooves being represented by the numeral 26 and the interior grooves by the numeral 27, the crank-shaft 10 in this form being provided with straight parallel ribs 11, which enter the grooves 27 on the interior of the sleeve 25. The eccentric 17 is also provided with ribs or projections 21, which enter the grooves 26 on the exterior of the sleeve 25. The encircling strap or band is designated by the numeral 18, and 19 designates the connecting-rod.

The invention having been thus described, what is claimed is—

1. A reversing mechanism comprising a valve-operating member and an eccentric-support provided with coöperating spiral

grooves and projections, and means for moving the support relatively to the member whereby the position of the axis of said member is varied.

5 2. A reversing mechanism comprising a crank-shaft, an eccentric-sleeve surrounding the crank-shaft, a main eccentric surrounding the sleeve, and means for connecting these elements whereby longitudinal movement of the sleeve will rotate the main eccentric.

15 3. A reversing mechanism comprising a crank-shaft, an eccentric-sleeve surrounding the crank-shaft, a main eccentric surrounding the sleeve, and means for connecting these elements whereby a longitudinal movement of the sleeve will rotate both said sleeve and the main eccentric.

20 4. A reversing mechanism comprising a crank-shaft, an eccentric-sleeve and a main eccentric successively surrounding and contacting with one another, each pair of contacting elements being provided with coöperating spiral grooves and projections.

25 5. A reversing mechanism comprising a crank-shaft, an eccentric-sleeve and a main eccentric successively surrounding and contacting with one another, each pair of con-

tacting elements being provided with coöperating spiral grooves and projections, means 30 for moving the sleeve longitudinally, and means for preventing longitudinal movement of the eccentric.

6. A reversing mechanism comprising a crank-shaft provided with spiral projections, 35 an eccentric-sleeve having spiral grooves engaged by said projections and external spiral grooves, and a main eccentric provided with projections entering the grooves in the exterior of the sleeve.

40 7. A reversing mechanism comprising a crank-shaft provided with spiral projections, an eccentric-sleeve having spiral grooves engaged by said projections and external spiral grooves, and a main eccentric provided with 45 projections entering the grooves in the exterior of the sleeve, and means for moving the sleeve, and stop members coacting with the eccentric.

In testimony that I claim the foregoing as 50 my own I have hereto affixed my signature in the presence of two witnesses.

JOHN ARTHUR BJUR.
